Arthur J. Kitson,
Inventor

By Franklin D. Hough

Attorney

UNITED STATES PATENT OFFICE.

ARTHUR J. KITSON, OF ANN ARBOR, MICHIGAN.

WEATHER-STRIP.

SPECIFICATION forming part of Letters Patent No. 728,244, dated May 19, 1903.

Application filed March 24, 1903. Serial No. 149,363. (No model.)

To all whom it may concern:

Be it known that I, ARTHUR J. KITSON, a citizen of the United States, residing at Ann Arbor, in the county of Washtenaw and State of Michigan, have invented certain new and useful Improvements in Weather-Strips; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in weather-strips, and especially in the provision of strips which are secured to a parting-rail and held thereto by means of a strip intermediate the sash of the window, thus entirely concealing the weather-strips, the edges of said strips working in grooves in the adjacent faces of the sash.

The invention consists, further, in various details of construction and arrangements of parts, which will be hereinafter fully described and then specifically defined in the appended claims.

My invention is illustrated in the accompanying drawings, which, with the letters of reference marked thereon, form a part of this application, and in which drawings similar letters of reference indicate like parts in the views, in which—

Figure 1 is a perspective view of portions of the sash of the window, parts being broken away to show the weather-strips, which are mounted on the parting-strip; and Fig. 2 is a transverse sectional view through the sash and weather-strip. Fig. 3 is a perspective view of the parting-strip and weather-strip-retaining bar, showing the weather-strips held thereto.

Reference now being had to the details of the drawings by letter, A designates the frame of a window, and B and B' the two sash, which are held spaced apart by means of a parting-strip C, which is seated in a channel in the frame, and in each adjacent face of the sash is formed a longitudinal groove or slot D of sufficient width and depth to receive the portion of the weather-strip E which projects laterally from the parting-

strip. The inner end of each weather-strip E is bent substantially at right angles, as at F, and said angled portion is adapted to enter channels H, which are formed on the inner face of the bar K. Said bar K is substantially the width of the parting-strip, the opposite edges being flush therewith, and is fastened to the parting-strip by means of screws N.

By the provision of a weather-strip embodying the construction described it will be observed that the strips D may be inserted in the longitudinal channels or grooves in the adjacent faces of the sash and the bar K, with the grooves on its inner face, fitted over the angled ends of the weather-strips and secured to the parting-strip by means of screws, and by this construction the weather-strips may be easily replaced and are securely held in place without screws or nails engaging the same, but are securely clamped and held, so that the laterally-projecting portions thereof will engage the channels of the sash and form guides for the same as they are raised and lowered.

While I have shown a particular detailed construction of weather-strip embodying my invention, it will be understood that I may make slight alterations in the various features without departing from the spirit of the invention.

Having thus fully described my invention, what I claim as new, and desire to secure by Letters Patent, is—

1. A weather-strip comprising, in combination with the frame and sash of a window, a parting-strip intermediate the sash, and weather-strips having their inner adjacent ends angled, and a channeled block adapted to be fastened to the weather-strip and the channels of said block receiving the angled ends of the weather-strips, the laterally-projecting portions of the weather-strips entering the grooves or channels in the sash and forming guides on which the sash slide, as set forth.

2. A weather-strip for windows, comprising, in combination with the frame and sash of a window, a parting-strip intermediate the sash, weather-strips having their outer longitudinal edges seated in channels in the ad-

jacent faces of the sash and having their inner ends angled, a bar having longitudinal and parallel slots therein adapted to receive said angled ends, and means for clamping said block against the parting-strip to hold the weather-strips securely in place, as set forth.

In testimony whereof I hereunto affix my signature in presence of two witnesses.

ARTHUR J. KITSON.
